US0D1070738S

(12) **United States Design Patent** (10) **Patent No.:** **US D1,070,738 S**
(45) **Date of Patent:** **** Apr. 15, 2025**

(54) **PHOTOVOLTAIC MODULE**

(71) Applicant: **G-STAR PTE. LTD.**, Singapore (SG)

(72) Inventor: **Huajun Tang**, Jiangsu (CN)

(**) Term: **15 Years**

(21) Appl. No.: **29/958,105**

(22) Filed: **Aug. 17, 2024**

(51) LOC (15) Cl. **13-04**

(52) U.S. Cl.

(57) **CLAIM**

The ornamental design for a photovoltaic module, as shown and described.

DESCRIPTION

FIG. 1 is a perspective view of a photovoltaic module showing the new design;

FIG. 2 is another perspective view thereof;

FIG. 3 is a front elevation view thereof;

FIG. 4 is a back elevation view thereof;

FIG. 5 is a left-side elevation view thereof;

FIG. 6 is a right-side elevation view thereof;

FIG. 7 is a top plan view thereof; and

FIG. 8 is a bottom plan view thereof; and,

FIG. 9 is an enlarged view of the encircled portion in FIG. 1.

The equal-length broken lines depict portions of the photovoltaic module that form no part of the claimed design.

The dash-dot lines in FIG. 1 and FIG. 9 illustrate the boundaries of the enlarged view indicators and form no part of the claimed design.
